INDUCTION FURNACE

Application filed December 7, 1928, Serial No. 324,439, and in Germany March 2, 1928.

This invention relates to induction furnaces, more particularly to the type known as ironless induction furnaces having no iron core, although one portion of the magnetic 5 path consists of iron.

The electric ironless induction furnaces having been employed for melting or heating metals and ores up to the present time, are generally worked with currents of high frequency and on that account are called high frequency furnaces. A furnace of this type consists essentially in a crucible being surrounded externally by an air or water cooled coil. For the production of the current of 10 high frequency a converter unit is necessary comprising, f. i. a motor and a high frequency generator. If a polyphase motor is used, it may be connected to a polyphase supply 15 system. It has been found that it is economically advantageous to work such furnaces with currents of normal frequency (50-60 cycles per second). It has also been proposed to work such furnaces with frequencies of 2×50=100 or 3×50=150 cycles per second. 20 Since with ironless induction crucible furnaces a converter unit is not required if the normal frequency is used, the coil has been connected to one phase of a polyphase current supply. In this way the polyphase current 25 installation is disadvantageously loaded, which leads, particularly with the single phase connection of furnaces of large output, to increased losses in the installation.

It is, therefore, an object of this invention 30 to provide an ironless induction furnace adapted to be connected systematically to a polyphase supply system without increasing the loss of the installation.

Another object of this invention is to provide 35 an ironless electric furnace making it possible to control the input of power according to the required power at any time.

The invention consists in subdividing the 40 coil of the furnace and connecting the parts together in a phase transformer circuit of

known type. It will be understood, however, that instead of providing one subdivided coil the crucible may be surrounded by two coils connected together in Scott's method for changing three-phase into two-phase circuits.

The invention will be readily understood by reference to the accompanying drawing which represents diagrammatically one embodiment of the invention.

The crucible 1 is surrounded by two coils 2 and 3 of copper strips or copper tube. The two coils are connected together in Scott's system. Between the two coils 2 and 3 are the two rings 4 and 5 which are made of 55 transformer sheet iron. The iron rings are separated by an air space or a layer of a non-magnetic material.

The field of the upper circuit is closed externally through the upper ring and the field of the lower circuit through the lower iron ring. The air space between these two iron rings is practically free from lines of force. The magnetic fields of the upper and lower circuit and of the currents flowing in the 60 melting bath which are relatively displaced in Scott's circuit system by 90°, are still more completely separated if the diameter of the lower part of the furnace is smaller than that of the upper part. By this arrangement the 65 magnetic screening action of the two iron rings is increased, since they exert a screening action both at right angles and also parallel to the central axis. The diameter of the iron rings may also be less than that 70 of the lower coil, whereby the screening action of the iron rings is still further increased. This is, however, not absolutely necessary; since the secondary currents only flow at the 75 periphery of the bath the fields produced are concentrated mainly at the periphery of the bath, near the iron rings and towards the centre of the bath are considerably reduced.

Between the crucible 1 and the coils 2 and 80 3 there are a heat insulating layer 6 and a 85 90

cylinder 7 of electric insulating material. The same electric insulating material can also be used to separate the coil windings. Also, the intermediate layers between the coils and the coil clamping devices can also be made of the same material shown at 8. The furnace is covered by the cover 9 of refractory material such as firebrick or the like. The base 10 can be made of the same material. The cover rests on annular segments 11. The furnace can be tilted around an axis 12 which is below the pouring spout.

The two coils are connected to the poly-phase current supply system by a three-pole switch 13. The lower coil can be wholly or partially connected by the switch 14, in order to adjust the power applied to the furnace. The upper coil can be included by closing the switch 15.

By tappings arranged within one or both coils the output can be controlled. For example, during the refining period in which less power is required, the upper coil can be cut off by the switch 15, the lower coil alone remaining in circuit. Phase compensation can be obtained, as in high frequency furnaces by condensers if the conditions require it.

What is claimed is:

1. In a coreless induction furnace, in combination, a crucible, two coils surrounding said crucible, a three-phase source of alternating current and a Scott connection whereby a two-phase Scott circuit may be applied to the coils.

2. In a coreless induction furnace, in combination, a crucible and two coils surrounding said crucible, a three-phase source of current and a Scott connection whereby a two-phase Scott circuit may be connected to the coils, the lower part of the furnace having a smaller diameter than the upper part, the two coils being applied about different furnace diameters.

3. In a coreless induction furnace, in combination, a crucible, two coils surrounding said crucible, rings of laminated magnetic material between the coils and a multi-phase source of current for the coils whereby the sections surrounded by the two coils are substantially free each of induction from the other coil.

4. In a coreless induction furnace, in combination, a crucible, two coils surrounding said crucible, a source of current for the different coils, and rings of laminated iron placed between said coils, the iron sheets being separated from one another by an air space.

5. In a coreless induction furnace, a crucible having the diameter of its upper portion larger than that of the lower portion, two inductor coils, one about each of the portions of the different diameters, a multi-phase source of current for the two coils and magnetic means between the coils for protecting

each coil from magnetic interference from current in the other coil.

6. In a coreless induction furnace, a crucible, two inductor coils surrounding the crucible, a source of Scott connected current for said inductors and connections whereby the current can be passed through the lower coil or through both coils at will.

In testimony whereof I affix my signature.

FRANZ LINNHOFF.
